UNITED STATES PATENT OFFICE.

FREDERICK J. KIESER, OF CHICAGO, ILLINOIS, ASSIGNOR TO KIESER-RICHTER COMPANY, A CORPORATION OF ILLINOIS.

TOBACCO-PIPE.

1,100,377.

Specification of Letters Patent. Patented June 16, 1914.

Application filed September 26, 1912. Serial No. 722,396.

To all whom it may concern:

Be it known that I, FREDERICK J. KIESER, a citizen of the United States, residing in the city of Chicago, county of Cook, State 5 of Illinois, have invented certain new and useful Improvements in Tobacco-Pipes, of which the following is a specification.

The object of this invention is to provide a tobacco pipe of simple construction where- 10 in the smoke is drawn off immediately below the fire from the circumference of the bowl, while provision is made for replen- 15 ishing the supply of tobacco in the fire chamber from below, and for ready access to all portions of the pipe for easy cleaning thereof.

In the drawing Figure 1. is a sectional side-elevation of my pipe; Fig. 2. is a horizontal section in the plane indicated by 20 line 2—2 in Fig. 1; and Fig. 3 is a sectional view of the stem in the plane indicated by line 4—4 in Fig. 1.

Referring to the drawing, into bowl 10 is threaded, from above, burner ring 11, the 25 interior of which is formed cylindrical for the lower, approximately three-fourths, portion thereof, while the upper, approxi- 30 mately one-fourth, portion thereof is formed in the shape of a cone-section,— contracting toward the opening at the top. In the cylindrical portion of ring 11 is 35 slidably mounted plug 12, held in place by split expansion-ring 13, mounted in a groove on the circumference of plug 12, and bearing 40 against the walls of ring 11. Below plug 12 there is preferably held, by shoulder 14 of bowl 10, ornamental plug 15, of a di- 45 ameter slightly less than plug 12. The top of ring 11 is enlarged and made of greater 50 thickness than the lower part, thereby forming shoulder 30, abutting the upper end of bowl 10. Slightly below the upper rim of burner ring 11 there are bored into it, at a 55 descending angle of about 45°, a series of channels 16, preferably three, being equi- 60 distant from each other, and leading from the exterior to the interior of ring 11, at the juncture of the conical and cylindrical 65 portions thereof. All of these channels are 70 located in vertical planes converging toward the axis of ring 11, and have their outer 75 ends closed by screw plugs 17. From each of these channels preferably two other channels 18 are branched off, which likewise lead 80 to the interior of ring 11, while another 85

channel 19 leads from the juncture of each channel 16 with channels 18 to channel 20, drained by means of channel 21 and per- 90 forated screw plug 22, screwed up against shoulder 23 when it is desired to close the drain. Channels 19, below shoulder 30, are 95 cut into the outer surface of ring 11, thus being easily accessible when ring 11 is removed from bowl 10. Smoke channel 24 leads from channel 20 to slightly tapering 100 stem chamber 25. Perforated stem 26 is preferably made with a considerable taper toward its lower end, and fitted into cham- 105 ber 25 by means of projecting feather 27 which will readily cut through any impuri- 110 ties adhering to the walls of chamber 25, thereby securing a firm seat for stem 26. The principal purpose of feather 27 is to adapt stem 26 to be used as a scraper for 115 cleaning the upper portion of ring 11. 120 Stem 26 is further provided at its lower end with projections 28, in order to adapt it to be used for pushing down plug 12 (after all 125 of the tobacco in the bowl has been burned up), without danger of clogging thereby the 130 lower end of the perforation in stem 26.

My pipe is used as follows:—Being 135 empty, it is filled with tobacco from the top, pushing down plug 12 to the bottom, and firmly pressing home the tobacco. The pipe 140 is then lighted, burning from the top down to the interior openings of channels 16 and 145 18. As the tobacco at the top is being consumed, plug 12 is pushed upward, either di- 150 rectly, by pressure of a thumb, or by means 155 of plug 15 (where the pipe is provided with it); plug 15 dropping back into place as soon as released, but plug 12 being held at any 160 point to which it may be pushed, by means of 165 the tension of ring 13 against the walls of 170 ring 11, until again displaced by superior 175 force. When the top of plug 12 has reached 180 the top of the cylindrical portion of ring 11, 185 all of the tobacco on top of it may be con- 190 sumed, and the pipe will be ready for an- 195 other charge. By unscrewing plugs 17 and 200 22 and ring 11, and removing stem 26, all 205 portions of my pipe become readily acces- 210 sible for a complete and thorough cleaning.

I claim:—

1. In a tobacco-pipe, the combination of 215 a bowl having suitable openings for a 220 burner ring and a stem, with a burner ring 225 having the upper portion of its interior con- 230 tracted toward the upper end thereof, and 235

having channels leading from its inner circumference near its top to a channel in the bowl connecting with the stem opening thereof; a slidable plug in the burner ring; means to hold said plug at any desired elevation within the burner ring; and a stem; substantially as, and for the purpose described.

2. In a tobacco-pipe, the combination of
a bowl having a substantially cylindrical
10 opening for a burner ring with an inwardly
projecting flange at the lower end of such
opening, and having a suitable opening for
a stem, with a burner ring having channels
leading from its inner circumference near its
15 top to a channel in the bowl connecting with
the stem opening thereof; a slideable plug
in the burner ring; means to hold said plug
at any desired elevation within the burner
ring; and a stem; substantially as, and for
20 the purpose described.

3. In a tobacco-pipe, the combination of a bowl having suitable openings for a burner ring and a stem, with a burner ring having channels leading in an upward direction from 25 its inner circumference near its top, and channels connecting such first mentioned channels with a channel in the bowl connecting with the stem opening thereof; a slidable plug in the burner ring; means to hold said 30 plug at any desired elevation within the burner ring; and a stem; substantially as, and for the purpose described.

4. In a tobacco-pipe, the combination of a bowl having suitable openings for a burner ring and a stem, with a burner ring having channels leading from its inner circumference near its top to a channel in the bowl connecting with the stem opening thereof, said channels being formed in part in the outer surface of the burner ring; a slidable plug in the burner ring; means to hold said plug at any desired elevation within the burner ring; and a stem; substantially as, and for the purpose described.

45. 5. In a tobacco-pipe, the combination of a bowl having suitable openings for a burner ring and a stem, with a burner ring having

channels leading from its inner circumference near its top to a channel in the bowl connecting with the stem opening thereof and 50 said bowl also having a drain-outlet closed by a perforated screw plug screwing against a shoulder; a slideable plug in the burner ring; means to hold said plug at any desired elevation within the burner ring; and a stem, 55 substantially as, and for the purpose described.

60 6. In a tobacco-pipe, the combination of a bowl having a substantially cylindrical opening for a burner ring with an inwardly projecting flange at the lower end of such opening, and having a suitable opening for a stem, with a burner ring having channels leading from its inner circumference near its top to a channel in the bowl connecting with the stem opening thereof; a slideable plug in the burner ring; means to hold said plug at any desired elevation within the burner ring; an ornamental plug below said first named plug; and a stem; substantially 65 70 as and for the purpose described.

7. In a tobacco-pipe, the combination of a bowl having a stem opening, with a stem having its lower end tapered so as not to fill said stem-opening, and being fitted into said stem-opening by means of a feather projecting sidewise from the lower part of the stem, substantially as and for the purpose described. 75

8. In a tobacco-pipe, the combination of 80
a bowl having a largely cylindrical tobacco-
chamber and a stem-opening, and having
channels leading from the tobacco-chamber,
near the top thereof, to the stem opening,
with a slid able plug in the tobacco-chamber; 85
means to hold said plug at any desired eleva-
tion in the tobacco-chamber; and a perfo-
rated stem having projections at its lower
end; substantially as and for the purpose
described.
